Patented Apr. 2, 1918.

UNITED STATES PATENT OFFICE.

LOUIS H. KETTNER, OF NEW ROCHELLE, NEW YORK.

DEVICE FOR CLEANING BOILERS.

1,261,243.

Specification of Letters Patent.

Patented Apr. 2, 1918.

Application filed March 25, 1916. Serial No. 86,572.

To all whom it may concern:

Be it known that I, LOUIS H. KETTNER, a citizen of the United States, and resident of New Rochelle, in the county of Westchester and State of New York, have invented a new and useful Improvement in Devices for Cleaning Boilers, of which the following is a specification.

This invention relates to a device for cleaning boilers, my more particular object being to produce a portable or removable device which may be readily inserted and attached to boilers, especially kitchen water boilers now in common use, and which provides a simple and efficient construction for accomplishing the work.

Another object is to provide a device which will be cheap to manufacture and easily assembled and taken apart for shipment or storage.

A further object consists in providing certain improvements in the form, construction and arrangement of the several parts whereby the above mentioned and other objects may be effectively carried out.

Kitchen water boilers now in common use for storage and supply purposes require cleaning more or less frequently. This type of boiler is sealed at the top and bottom except for the inlet and outlet pipes. This cleaning operation usually requires that the boiler must first be emptied and then the labor of two or more men utilized to disconnect all feed water pipes and remove the boiler from its stand or hanger, after which the boiler must be replaced and refilled. This operation generally consumes from four to six hours. There is, hence, quite a large expense involved in labor, time and loss of water.

My invention includes improved means for effecting the mechanical loosening of the sediment which is drawn and washed out, while the device is being manipulated by the operator.

A practical embodiment of my invention is represented in the accompanying drawings, in which—

Figure 1 represents a side elevation of a kitchen boiler, partly in section, showing the inlet and service pipes as in common use.

Fig. 2 represents a detail central section of the lower portion of a boiler with the spud, cleanout pipe and drain cock removed, and my device applied therein.

Fig. 3 represents a horizontal section taken in the plane of the line A—A of Fig. 1, and

Fig. 4 represents a horizontal section taken in the plane of the line B—B of Fig. 1, looking in the direction of the arrows.

The boiler is denoted by 1, the feed pipe by 3, the service pipe by 4, the spud by 5 and cleanout or drain pipe by 6.

To apply my device, the spud 5 and cleanout pipe 6 are removed and in the threaded hole where the spud 5 was removed, I insert a nipple 7. Upon this nipple 7 is screwed an elbow 8 having a worm or feed screw 9, which is provided with a stem 10 extending downwardly through the elbow in position to receive an arm 11 removably secured thereto by means of a cotter pin 12. This arm 11 forms a crank and for convenience I pivot at 13 a handle 14, by which the crank is operated.

The upper end of the feed screw 9 is flattened, as shown at 15, to which is pivotally secured a yielding breaker 16, which is bent to form a spiral so that in the rotation of the breaker, the sediment will be dislodged, broken up and forced toward the center, where it is drawn through the nipple 7 by the feed screw 9 into the elbow 8 and forced out through the outlet pipe 17 into a receptacle (not shown). The outer or free end 18 of the breaker 16 is turned up, so that the sediment may be dislodged at or near the vertical wall of the boiler.

Should the feed screw 9 become clogged with sediment of a heavy nature, provision is made in the length of the stem 10 so that it may be raised and lowered vertically in the elbow 8, thereby dislodging the same and freeing the screw, or the screw may be rotated in the opposite direction, which will force the sediment upwardly and thus clean the passage.

After the feed screw 9, with its yielding breaker 16, has been rotated sufficiently to loosen the sediment, water may be admitted to flush the boiler and thus wash such loose sediment that has not been drawn or passed out through the screw.

I preferably make the breaker 16 of material, such as spring steel, so that if it should meet some obstacle that is too hard to remove, it will spring over it, thereby saving it from being bent or broken; at the same time it will strike the sediment with a sharp blow as it springs by the obstacle,

thus causing the sediment to be broken up more efficiently.

While I have shown the arm 11 as having a handle 14 pivoted thereto, it is not essential, as the arm 11 may be manipulated by the operator without the handle. The handle 14 need only be used in places where it is difficult to operate the arm, as, for instance, where the boiler is located upon a stand, as shown in Figs. 1 and 2 of the drawings. It will also be understood that in cases where the spud 5 is not removed, the elbow 8, with the feed screw therein, may be screwed directly thereon.

It is obvious that various changes may be resorted to in the form, construction and arrangement of the several parts, without departing from the spirit and scope of my invention; hence I do not intend to limit myself to the particular details herein shown and described except as they may be set forth in the claims.

What I claim is:

1. A device of the character described comprising an elbow having an inlet and an outlet, a vertically disposed feed screw

interposed between said inlet and outlet, said feed screw having a stem journaled in said elbow and extending therethrough, a yielding spirally formed breaker secured to the upper end of said feed screw above the inlet, and means on the lower end of the stem for manipulating the screw and breaker.

2. A device of the character described comprising an elbow having an inlet and an outlet, a vertically disposed feed screw interposed between said inlet and outlet, said feed screw having a stem journaled in said elbow and extending therethrough, a yielding spirally formed breaker secured to the upper end of said feed screw above the inlet, the free end of said breaker being provided with an upwardly turned end to engage the side walls of the boiler, and means on the lower end of said stem for manipulating the screw and breaker.

In testimony that I claim the foregoing as my invention, I have signed my name this 20th day of March, 1916.

LOUIS H. KETTNER.
